(**) Term: **14 Years**

CLAIM

(21) Appl. No.: **29/162,410**

The ornamental design for a tool for dispensing adhesives, sealants, and underfill materials, as shown and described.

(22) Filed: **Jun. 14, 2002**

DESCRIPTION

(51) LOC (7) Cl. **15-09**

FIG. 1 is an elevational view of a first end for the new design
for a tool for dispensing adhesives, sealants, and underfill
material;

(52) U.S. Cl. **D15/144.2**

FIG. 2 is a top plan view of the tool as shown in FIG. 1;
FIG. 3 is a bottom view;

(58) Field of Search D15/144, 144.1,
D15/144.2; 118/313, 323, 697; 222/146.5,
189, 482, 504; 427/186, 208.2; 901/43

FIG. 4 is a right side elevational view wherein the left
elevational view is a mirror image; and,
FIG. 5 is a rear elevational view.
